Specification for Design.

Patented Nov. 30, 1909.

Application filed September 11, 1909. Serial No. 517,720. Term of patent 3½ years.

To all whom it may concern:

Be it known that I, DAVID W. KEITH, a citizen of the United States, residing at Plankinton, in the county of Aurora and State of South Dakota, have invented a certain new and original and ornamental Design for a Reservoir for Fountain-Syringes, of which the following is a specification.

In the accompanying drawings I have shown in Figures 1, 2, and 3, respectively, a

top, front, and side view of a fountain syringe reservoir showing my new design.

I claim:

The ornamental design for a fountain syringe reservoir as shown.

DAVID W. KEITH.
